United States Patent Office

Des. 191,477
Patented Oct. 3, 1961

191,477

PORTABLE COOLER

Lawrence W. Bonzer, Long Beach, Calif., assignor to G & B Manufacturing Co., Inc., Long Beach, Calif., a corporation of California

Filed Jan. 17, 1961, Ser. No. 63,585

Term of patent 14 years

(Cl. D62—4)

FIG. 1.

FIG. 2.

FIG. 3.

I claim:

The ornamental design for a portable cooler, substantially as shown.
